COMBINED DISPLAY UNIT AND DOLLY THEREFOR

Charles L. Davis, Atlanta, Ga., assignor to The
Coca-Cola Company, Atlanta, Ga.

Filed Sept. 10, 1975, Ser. No. 612,120

Term of patent 14 years

Int. Cl. D9—03; D12—02; D20—02
U.S. Cl. D6—154

FIG 1

FIG 2

FIG 3

FIG 4

FIG. 1 is an enlarged exploded perspective view of a combined display unit and dolly therefor showing my new design, the lettering and cartons of bottles are shown in broken lines for illustrative purposes only and do not form a part of the claimed design.

FIG. 2 is a perspective view thereof.

FIG. 3 is a perspective view with a portion of the handle-like element folded down to form a shelf.

FIG. 4 is a perspective view in the closed position.

FIG. 4 is a perspective view in the closed position. In FIGS. 2-4, the dolly is omitted for ease of illustration.

The rear of the claimed article which is not disclosed is shown unrepresented.

I claim;

The ornamental design for a combined display unit and dolly therefor, as shown and described.
